SAFETY ANCHOR

Application filed November 8, 1927. Serial No. 231,980.

The invention relates to a safety anchor designed to be secured to a metallic window frame construction or the like, and which is adapted to receive the clips and other attachments such as are carried on the ends of safety belts used by window cleaners. The present disclosure constitutes an improvement in and an addition to the invention disclosed in my co-pending application on safety anchor mountings, bearing Serial No. 205,831 filed July 14, 1927.

In the above identified application, as well as in this application, there is featured a safety anchor construction particularly designed for installation on thin sheet metal window frames and where it is desired to provide a secure mounting for the anchor. The anchor is positioned to extend over a relatively large area of metal frame so as to relieve tearing strains on the thin sheet metal. This is attained by positioning a rugged metallic reinforcement on the inner side of the window frame, mounting a strong anchor on the opposing outer side and securing these rugged parts by screws passed therethrough. It is the usual practice to tighten the screws under tension and thus hold the sheet metal firmly clamped between the internal reinforcement and the external anchor.

It has been found that under some circumstances, as for instance, where the anchor is subjected to jars and laterally directed strains while in use that the tensioned screw has a tendency to rerotate, releasing the tight clamping engagement with the window frame, resulting in a loosening of the parts and permitting the formation of rust in the joined surfaces between the anchor and window frame.

Accordingly, the primary object of the invention is to provide a construction of the type outlined which will insure the maintenance of the parts in their initially set clamped position.

Another object of the invention is to provide a simplified construction of safety anchor which can be readily cast and which will provide screw locking features capable of being readily hammered or peened into operative position and at the same time

strengthen the anchor at the point where it is most likely to be weak.

Various other objects and advantages of the invention will be in part obvious from an inspection of the accompanying drawings and in part will be more fully set forth in the following particular description of one form of mechanism embodying my invention, and the invention also consists in certain new and novel features of construction and combination of parts hereinafter set forth and claimed.

In the accompanying drawings:

Fig. 1 is a transverse sectional view taken on the line 1—1 of Fig. 2 and showing a preferred embodiment of the invention;

Fig. 2 is a fragmentary view in front elevation of the safety anchor shown in Fig. 1; and

Fig. 3 is a view mainly in side elevation of the anchor shown in the preceding figures with parts broken away to show one of the screw locking lugs featured in this application.

In the drawings and referring particularly to the showing in Fig. 1, there is shown part of a corner of a window frame 10, it being understood that such frames are customarily formed of an extremely thin gauge of metal 11. Positioned within the corner 12 of the frame is a reinforcing element 17 secured in place by means of a bolt and nut fastener 25. A metallic casting 16 constituting an anchor is positioned on the outer face of the frame and is secured to the inner reinforcement 17 by a pair of screws 28 passed through apertures in the frame. A curved post 17' projects laterally from the base plate 15 of the anchor and otherwise the structure is of the form more fully disclosed in the above identified application.

In forming the anchor with its relatively long rectangular base plate 15, there is cast integral therewith a pair of relatively thin upstanding lugs 29 and 30 which are positioned at the narrow ends of the plate 15 and between each end and the adjacent screw hole 30'. These lugs are rectangular in cross section adjacent their end nearest the base plate with their greatest width parallel to the

adjacent narrow end of the plate so that they may be readily bent about their long apex or crotch 31 and thus moved from the upstanding solid line position shown in Fig. 3 into the dotted line position overlapping the head 32 of the adjacent screw. The usual practice after the screws have been tightened is to hammer the lugs into engagement with the top of the screws and thus engage the same 10 to prevent rerotation of the screws out of their clamping position.

By means of device of this character, it is possible to retain all of the advantages recited in the above identified application and 15 at the same time to provide a locking of the screws in position and the locking means will in no way interfere with the quick engaging of the clip with the post. The reinforcing of the narrow body of material between each 20 of the screw holes and the adjacent end of the anchor base plate by the lugs tends to give strength and rigidity to the anchor as a whole.

I claim:

25 1. A window frame including a sheet metal form provided with a pair of apertures, an internal reinforcement for the frame having a flat face in engagement with and extending across the part provided with the apertures, 30 an anchor engaging the side of the form opposite the reinforcement, and a pair of fastening means passed from the outside of the frame through the anchor, through the two apertures and extending into the reinforcement, said means acting under tension 35 with each secured in said tensioned position, and coacting to secure the anchor and reinforcement with the metal form fixedly clamped therebetween at the two apertures.

40 2. A window frame including a sheet metal form, an internal reinforcement and an external anchor having flat surfaces positioned on opposite sides of the form, fastening means engaging the reinforcement and 45 anchor for securing the form clamped therebetween and means integral with the anchor and adapted to be moved into position engaging the fastening means for securing the reinforcement and anchor in said form 50 clamping position.

Signed at New York, in the county of New York and State of New York, this 20th day of October, A. D. 1927.

A. BARDELLO.
